UNITED STATES PATENT OFFICE.

THOMAS JAMES CRAIG AND ARTHUR L. SCOFIELD, OF MERCED, CALIFORNIA.

SCREEN FOR SEPARATING ALMONDS AND HULLS.

Application filed March 3, 1926. Serial No. 91,890.

This invention relates to improvements in screens and particularly to a screen for use in separating almonds from hulls which are mixed therewith after the almonds have been primarily screened to remove the hulls therefrom after leaving a hulling machine. During the latter screening operation a certain number of small almonds will pass through the screening holes (usually round). 10 The most common way now employed to salvage these almonds is to hand-pick them, which method however is slow, tedious and costly.

The almonds which are mixed with the hulls are, of course, small and therefore to separate them by screening requires a peculiar type of screen which will positively move the hulls therethrough, but of a fine enough mesh to hold the almonds and allow 20 them to be discharged into containers free of the hulls.

It has therefore been the principal object of our invention to provide such a screen, and this we believe we have accomplished by 25 making a screen consisting essentially of elongated slits narrow enough to hold the almonds from passing therethrough but wide enough to pass the hulls edgewise therethrough and so constructed as to positively move the hulls to edgewise position so that they will drop through the slits and not hang thereon and thus clog the screen. 30

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claim. 40

In the drawings similar characters of reference indicate corresponding parts in the several views:

Fig. 1 is a side elevation of the screen showing one way by means of which it can be shaken and gyrated, to settle the hulls through the screen and move the clean almonds therefrom.

Fig. 2 is a plan view of one small section 50 of the screen.

Fig. 3 is a similar view of a modified type of screen.

Fig. 4 is a sectional view taken on a line 4-4 of Fig. 3.

Fig. 5 is a sectional view of an almond 55 hull hung up on a screen web.

Referring now more particularly to the characters of reference on the drawings, the numeral 1 designates the screen and its frame as a whole. In practice this screen and frame will be mounted on supporting springs or like structure 2 and will be arranged for a shaking and gyrating movement thereon actuated by a push rod 3 operated from an eccentric cam 4 driven by a pulley 5 connected with any suitable source of power, not shown. This specific operating structure is no part of our invention and may be substituted by any other operating means found desirable. 70

Our improved screen proper comprises a body of thin sheet metal 6 cut into which are a plurality of thin slits 7 just sufficiently wide to allow almond hulls to comfortably pass edgewise therethrough, but narrow 75 enough to retain small almonds on the top of the screen.

The connecting webs 8 between the slits 7 are relatively wide and must be of a width greater than the width between the sides of a partly opened average almond hull so that it will be impossible for the hull to suspend or hang over the web as shown in Fig. 5, since when this happens the hulls will at once clog the screen and render it inoperative. 85 Therefore this feature of the relatively wide web constitutes the main novelty of our screen over other screens and as far as our contact with the almond screening industry goes we have never seen a like structure with the same function. 90

With our screen constructed as described the shaking and gyration of the screen causes the flat sides of split hulls to turn edgewise and drop through the slits 7. A 95 partly open hull comprising the two halves connected along one edge will shake along the relatively wide webs and since it cannot straddle and hang up on the same one edge of the hull will gradually get into a slit 7 100 and creep around the thin edge of the sheet metal until the hull turns to reverse position underneath the screen whereupon it will fall through and clear the screen. The nuts will of course pass off of the screen and can 105 be conveyed to suitable containers, not shown.

In the modified form of screen shown in

Figs. 3 and 4, 1^a designates the screen body and frame, 6^a the screen proper, 7^a the slits and 8^a the webs. In this form of screen the webs 8^a have upstruck curved ribs 9 thereon on the top face of the screen. These curved webs will assist in making positive and assisting in the creeping action of the partly open hulls described by positively directing them toward the edges of the webs.

10 From the foregoing description it will be readily seen that we have produced such a device as substantially fulfills the objects of the invention as set forth herein.

15 While this specification sets forth in detail the present and preferred construction of the device, still in practice such deviations from such detail may be resorted to as

do not form a departure from the spirit of the invention as defined by the appended claim.

Having thus described our invention what we claim as new and useful and desire to secure by Letters Patent is:

A screen for the purpose noted comprising a thin flat body provided with narrow slits, relatively wide webs between the slits, and upstruck curved ribs on the upper sides of the webs leaving a part of the flat plane of the webs between the edges of the ribs and the edges of the slits:

20 In testimony whereof we affix our signatures.

THOMAS JAMES CRAIG.
ARTHUR L. SCOFIELD.
